Primary Examiner — Sharon S Oum(74) *Attorney, Agent, or Firm* — Studebaker & Brackett
PC(57) **CLAIM**

The ornamental design for a casing for blower, as shown and described.

DESCRIPTIONFIG. 1. is a first perspective view of the front, left, and top sides of a casing for blower showing our new design;
FIG. 2. is a second perspective view of the front, right, and bottom sides thereof;

FIG. 3. is a front view thereof, a rear view being a mirror image thereof;

FIG. 4. is a left side view thereof;

FIG. 5. is a right side view thereof;

FIG. 6. is a top plan view thereof;

FIG. 7. is a bottom plan view thereof;

FIG. 8. is a cross-sectional view at 8-8 in FIG. 3; and,

FIG. 9. is a cross-sectional view at 9-9 in FIG. 4.

1 Claim, 9 Drawing Sheets(56)
